UNITED STATES PATENT OFFICE

OTTO TAUSCHEK, OF MUNICH, GERMANY, ASSIGNOR TO ONEIDA COMMUNITY, LIMITED, OF ONEIDA, NEW YORK, A CORPORATION OF NEW YORK

DESIGN FOR A DISH OR SIMILAR ARTICLE

Application filed July 15, 1931. Serial No. 40,548. Term of patent 14 years.

To all whom it may concern:

Be it known that I, OTTO TAUSCHEK, citizen of the Republic of Germany, residing at Munich, Bavaria, have invented a new, original, and ornamental Design for a Dish or Similar Article, of which the following is a specification, reference being had to the accompanying drawing, forming part thereof, said drawing being a plan view of a dish showing my new design, the essential feature of which is the ornamental figures extending around the face of the dish but shown only for a portion thereof in said drawing.

I claim:

The ornamental design for a dish or similar article as shown and described.

In testimony whereof I have hereunto set my hand.

OTTO TAUSCHEK.
